UNITED STATES PATENT OFFICE.

FRIDRICK H. B. BABBE, OF SANGER, CALIFORNIA.

SWIMMING APPARATUS.

SPECIFICATION forming part of Letters Patent No. 634,128, dated October 3, 1899.

Application filed June 26, 1899. Serial No. 721,843. (No model.)

To all whom it may concern:

Be it known that I, FRIDRICK H. B. BABBE, a citizen of the United States, residing at Sanger, Fresno county, State of California, have 5 invented an Improvement in Swimming Apparatus; and I hereby declare the following to be a full, clear, and exact description of the same.

My invention relates to an improved apparatus to aid in swimming.

It consists of a palm-piece having radially-pivoted ribs extending outwardly therefrom, a flexible and foldable covering for the ribs, and means for securing and holding the device in the hands of the swimmer.

It also comprises details of construction, which will be more fully explained by reference to the accompanying drawing, in which the figure illustrates my invention.

20 A is the palm-piece, which is made of any suitable material and, as here shown, segmental in its outer periphery, the inner portion being approximately straight, so that it may be grasped in the hand.

25 B are ribs extending radially outward and pivoted in a slot made in a curved outer periphery of the handpiece, so that they are turnable about their pivots. These ribs may be of any desired number, preferably five, 30 leaving four spaces between them, through which the fingers of the swimmer may pass, while the straightedge of the palm-piece lying within the palm of the hand the thumb will extend up on the opposite side thereof, so as 35 to hold it as firmly as may be desired.

The rib B nearest to the thumb is fixed and the other ribs movable, so as to be opened from or closed against the fixed rib.

40 When closed, the device is in small compass and easily portable.

Upon the radial ribs is fixed a flexible covering C, which will fold when the ribs are closed together similar to a fan and may be extended when the ribs are opened outwardly.

45 The device is maintained in an extended position partly by the fingers passing between the ribs exterior to the convex edge of the palm-piece and interior to the inner edge of the flexible covering material and partly by 50 the action of a spring D, one end of which is attached to the outermost of the ribs B and the other is adjustably connected with the

palm-piece, so that any desired tension may be given it to retain the device extended with a yielding pressure.

55

E is a strap or other device fixed to the palm-piece and extending backwardly, adapted to be secured to the wrist of the swimmer, so that when desired the grasp upon the device may be released and it will hang suspended from the wrist, leaving the hands free for other uses.

In construction the rib B, nearest the thumb, extends nearly straight outwardly from the palm-piece and more nearly parallel with the 65 inner edge of this piece than radially toward the exact center; but the outer rib nearest the little finger extends outwardly more nearly at right angles with the outer edge of the palm-piece, thus projecting considerably 70 beyond the outer side of the hand. The object of this construction is to assist in feathering or bringing the device edgewise to the water when the hands are moved forward, this effect being produced by the greater 75 pressure upon the outer edge of the device, which tends to turn the hand so as to bring it in line with the plane of forward movement. As soon as the backward movement of the hands commences the pressure upon 80 this projecting outer edge tends to swing it back again at right angles with the direction of movement of the hands, and it thus acts to bring the device into proper position to exert its force against the water without any 85 undue effort in turning the hands. This is an improved arrangement, making it much easier for the swimmer and using less exertion while swimming.

Having thus described my invention, what 90 I claim as new, and desire to secure by Letters Patent, is—

1. A swimming device consisting of a palm-piece having a straight inner edge, and a semicircular outer periphery, a channel 95 formed in said outer periphery, radial bars pivoted in said channel, a flexible covering fixed to said bars and leaving a space between the palm-piece and the inner edge for the insertion of the fingers of the hand.

100

2. A swimming device consisting of a palm-piece having a straight inner edge, a semicircular outer periphery, a channel or groove formed in said outer periphery, bars extend-

ing radially outward from the outer periphery, with interspaces sufficient to allow the insertion of the fingers between said bars, the innermost of said bars being fixed, and the others turnable about their pivot-pins, and a flexible covering uniting said bars.

3. A swimming device consisting of a palm-piece having the straight inner edge, a convexly-curved outer periphery, a groove or channel made in said outer periphery, a radial bar fixed in said outer groove, a bar adjacent to the thumb extending approximately parallel with the side of the palm-piece, and

the bar upon the opposite side extending approximately at right angles with the opposite edge of the palm-piece, a flexible covering uniting said bar and a spring attachment to the outermost bar by which the device is held extended when in use.

In witness whereof I have hereunto set my hand.

FRIDRICK H. B. BABBE.
